AUXILIARY MUSIC RACK

Fonville Winans, Fort Worth, Tex., assignor to
 Jenkins Music Company, Kansas City, Mo., a
 corporation of Missouri

Application March 15, 1937, Serial No. 130,830

3 Claims. (Cl. 45—82)

My invention relates to music racks and more particularly to auxiliary music racks for pianos.

The music rests provided on the music desks of pianos are primarily designed for adults. 5 Children and near sighted persons have difficulty in using the music rests provided. There is a tendency to lean forward, thus causing a particularly unfavorable condition. Not only is the position at the piano improper but in leaning forward and looking upwardly an undue amount of energy is necessary, inducing fatigue and early robbing the child of its ability to concentrate at the music lesson. The correct distance of music from the player's eyes should be sixteen inches. 10

One object of my invention is to provide a music rack which can be adapted to the music rest of the music desk on all pianos, including both the grand piano type and the upright piano type.

Another object of my invention is to provide a music rest which is light in weight, can be easily adjusted and will not scratch or injure the piano.

Other and further objects of my invention will appear from the following description.

In the accompanying drawing, which forms part of the instant specification and is to be read in conjunction therewith and in which like reference numerals are used to indicate like parts 30 in the various views;

Figure 1 is a view of the rear of my music rack with parts in folded position.

Figure 2 is a side elevation of the music rack shown in Figure 1 with parts in extended position.

Figure 3 is a sectional view on an enlarged scale, taken along the line 3—3 of Figure 1.

Figure 4 is a sectional view on an enlarged scale, taken along the line 4—4 of Figure 2.

Figure 5 is an elevation of my music rack in 40 position on a grand piano.

Figure 6 is a side elevation of my music rack in position on an upright piano.

In general, my invention contemplates the provision of supporting means adapted to clamp 45 upon the music rack of a piano which may be adjusted both as to height and as to angle.

More particularly referring now to the drawing, a tube 1 houses a rod 2 telescoped therein. The housed end of rod 2 is provided with an enlarged portion 3 adapted to prevent the rod from withdrawing from the tube 1. A set screw 4 is 50 adapted to clamp the rod 3 in any given position with respect to tube 1. To the outer end of rod 2 is hinged a bracket 5. A set screw 6 is adapted 55 to clamp the bracket in any set position. To the

bracket 5 is secured, by rivets 7, a music rack 8. The bracket 5 is provided with a bent portion 9 through which the rod 10 is adapted to slidably pass. The bent portion 9 carries a set screw 11 adapted to clamp the slidable rod 10 in any 5 set position. Pivoted to the tubular member 1 is a clamp 12 provided with a clamping screw 13. The inside of the clamp 12 is provided with a felt 14, and the outer end of clamping screw 13 is provided with a felt 15 so that, when the clamp 10 is fastened to a part of the piano, as will be hereinafter more fully described, the finish of the piano will not be marred.

Slidable rod 10 carries at its lower end a foot 16 which is provided with a felt covering 17 to 15 prevent its marring the finish of the piano. The back of the music rack 8 is provided with a pair of felt strips 18, likewise to prevent marring the finish of the piano on which the music rack is employed.

In use, considering now the music rack in connection with a grand piano, the clamp 12 is placed in position over the top of the music rest 19 of the piano. These music rests are usually pivoted. In order to prevent the music rest 19 from tilting, the rod 10 is extended so that the foot 16 will rest on the piano music desk or on top of the fall board of the piano, as shown in Figure 5. The adjustment is such that the effective length of the distance from the clamp 30 to the foot 16 will be sufficient to cause these parts to act as a brace, it being understood that set screw 4, set screw 6, and set screw 11 are set up tight. The parts will then be in the position shown in Figure 5 and it will be observed that 35 music may be placed upon the music rack 8 at a distance much closer to the player than it would occupy were it placed against music rest 19 of the piano proper. If it should be desired to lower the music still further, set screws 4 and 11 are 40 loosened, permitting rod 2 to move out of tube 1 and bracket 5 to slide over rod 10. When the desired height is reached, these set screws are tightened and the rack will remain in the set position. Set screw 6 governs the angle the rack 45 will assume. Obviously, this angle can be readily changed by simply loosening set screw 6, making the desired adjustment and resetting it.

In connection with an upright piano, the clamp 2 is clamped upon the upper portion of 50 the piano and then the lid 20 is closed. The tube 1 and the rack will then be supported from the clamp as shown in Figure 6. The height of the rack can be readily adjusted by simply adjusting the position of rod 2 within tube 1 by means 55

of set screw 4. The angle of the rack can be readily adjusted through set screw 6. It will be observed that the foot 16 and the rod 10 need not be employed in connection with an upright piano unless desired. If desired, the set screw 11 may be loosened and foot 16 permitted to rest against the fall board or other portion of the piano to prevent the rack from swinging.

The rack further may be used as a table music rack by simply moving tube 1 and rod 2 outwardly, making it act as a supporting leg, clamping it in any desired position. The angle at which the rack rests may be governed either by the angle to which the rod 2 is moved or by extending the effective length of the leg by moving tube 1 outwardly over rod 2 and adjusting it to any desired position by means of set screw 4.

It will be observed that I have accomplished the objects of my invention, providing a rack which may be adjusted to any desired height and to any desired angle, and which may be employed not only in connection with all types of pianos, both upright and grand, but also may be employed as a table rack. The construction is such that it will not scratch the piano; it is light in weight and is easily adjusted, and will provide a music rack which will enable children to have music properly positioned, thus avoiding nervous strain and fatigue occasioned by improperly positioned music.

It will be understood that certain features and subcombinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is

not to be limited to the specific details shown and described.

Having thus described my invention, what I claim is:

1. A music rack including in combination a clamp adapted to be secured to a pivoted music rest of a piano, a supporting member hingedly attached to said clamp, means for varying the length of said supporting member, a music rack, means for adjustably positioning said music rack on said supporting member, and adjustable means carried by said rack adapted to engage a portion of said piano for preventing the piano music rest from pivoting. 5 10

2. In an auxiliary music rack adapted to be used in connection with a pivoted music rest of a piano, a clamp adapted to be secured to the piano music rest, a supporting member hingedly attached to said clamp, means for varying the length of said supporting member, a bracket positioned on said supporting member for angular adjustment therewith, a music rack carried by said bracket, a supporting foot mounted in said bracket for movement therein, and means for securing said foot in any set position in contact 20 25 with a portion of the piano for preventing the music rest from pivoting.

3. A music rack including in combination a clamp adapted to be secured to a pivoted music rest of a piano, a supporting member hingedly attached to said clamp, means for varying the length of said supporting member, a bracket hingedly carried by said supporting member, means for clamping said bracket in any set position, a music rack carried by said bracket, and 30 35 a member mounted for movement into engagement with a part of the piano for preventing the music rest from pivoting.

FONVILLE WINANS.
